UNITED STATES PATENT OFFICE.

ANDRÉ BELTZER, OF QUINCY, MASSACHUSETTS, ASSIGNOR TO INDUSTRIAL OXYGEN COMPANY, OF NEW YORK, N. Y., A CORPORATION OF ILLINOIS.

OXYGEN-GENERATOR.

No. 895,331.

Specification of Letters Patent. Patented Aug. 4, 1908.

Application filed November 15, 1906. Serial No. 343,601.

To all whom it may concern:

Be it known that I, ANDRÉ BELTZER, a citizen of the Republic of France, residing at Quincy, in the county of Norfolk and State of Massachusetts, have invented certain new and useful Improvements in Oxygen-Generators; and I do hereby declare the following to be a full, clear, and exact description of the invention, such as will enable others skilled in the art to which it appertains to make and use the same.

The object of the invention is to produce a neat, simple and reliable oxygen generator for medical purposes and the like, which shall be inexpensive to manufacture and easily manipulated and which shall be so constructed that the generation is automatically stopped when the consumption ceases.

In the drawing, which is a central vertical section of the generator, the outer cylindrical casing *a* has supported in it a vertical take-off pipe *b* which is connected with a horizontal tap *b'* passing through the wall of the casing and provided with a cock *c*. The cover *d* is provided with a flange *d'* which fits snugly within the open upper end of the cylindrical casing, and this cover carries the axially arranged cylindrical gas collecting chamber *e*.

The oxygen generating material with which the apparatus is intended to be used is the compound disclosed and claimed in U. S. Letters Patent, No. 691,058, granted to George F. Jauber on January 14, 1902 which compound is known as oxylithe. This compound is made in the form of small square cakes which are indicated at *g* in the receptacle *f*. This receptacle is detachably secured to the chamber *e* by the bayonet joint *n* which is provided with a spring clip *o* which engages the pin *n* to lock it in place. The receptacle *f* extends below the chamber *e* quite or nearly to the bottom of the casing *a*, and is provided at about the level of the lower end of the casing *e* with a horizontal partition *h* which has a number of perforations *h'* for the passage of water. Two concave circular disks *i* provided with perforations as shown, are swiveled to the partition above and below the perforations *h'*. The spaces between these disks and the partition are stuffed with asbestos or similar pervious material through which the water may seep, and the passage of the water may be regulated by turning these disks toward or away from a position in which the several perfora-

tions register, in a manner which will be readily understood. The lower end of the receptacle *f* has a plurality of notches *k* to establish communication between the interior of the receptacle and the cylindrical casing. It will be observed that these openings are restricted in size and are considerably below the level of the partition *h*.

The cover *d* is detachably secured to the casing by the spring clips *l* which have sufficient grip to prevent the lifting of the cover by the pressure of the accumulated gas, and yet permit ready removal of the cover without the unscrewing of any part or any complicated manipulation. The cover is provided with a vent *m* to permit an equalization of pressure within the cylindrical casing outside of the gas collecting chamber as the water level therein rises and falls.

An auxiliary chamber *p* adapted to sit over and surround the vertical take-off pipe *b*, is formed by securing a bent piece of metal *p'* to the side of the chamber *e* and to the cover as shown, and a restricted orifice *r* is formed between the chamber *e* and the auxiliary chamber *p*.

The operation is as follows:—One or more blocks of oxylithe, the number depending upon the oxygen it is desired to generate, are placed within the receptacle *f* resting on the partition *h*. This receptacle is then attached within the gas collecting chamber by the bayonet joint. The cylindrical casing is then filled about half full of water, and the cover carrying the receptacle *f* is put on and caught under the clips *l*. The water immediately rises through the openings *k* and *h'*, within the receptacle *f* and into contact with the oxylithe. The oxygen which is thus generated is collected and passes through the restricted opening *r* into the auxiliary chamber *p* which is sealed at the bottom by the water. If the cock is opened the oxygen passes out through the pipe *b* and the generation continues. If the cock *c* is closed, the pressure of the gas accumulated in the chamber, which pressure is retained by the clips *l* forces the water out of the receptacle *f* until it is below the level of the partition *h*. The fact that the openings between the interior of the receptacle *f* and the cylindrical casing are considerably below the partition *h* prevents the escape of the gas below the lower edge of the chamber *e*, and thus affords a water seal. As the oxylithe is dissolved, the cakes drop

down to the partition h until the oxylithe is entirely consumed, then the cover may be removed, the liquid residue emptied, and the apparatus prepared for a further operation.

5 It will be observed that the apparatus is simple in arrangement, reliable, and in every way adapted for general use by medical practitioners, and the like, and that its simplicity also renders it inexpensive to manufacture 10 and commercially valuable.

What I claim is:—

1. In a portable oxygen generator for medical purposes and the like, a cylindrical casing, a vertical take-off pipe secured within 15 said casing at one side thereof, and a horizontal tap connected to said pipe and extending through the wall of the casing, in combination with a cover for the casing, a tube forming a gas collecting chamber depending from 20 the cover and open at its lower end, a receptacle detachably secured to said tube, a partition in said receptacle, water passages through said partition, and a bent sheet of metal secured to one side of the said tube 25 to form an auxiliary chamber adapted to fit over the vertical take-off pipe when the cover is in place, the walls separating the gas collecting chamber from the auxiliary chamber having a restricted passage, substantially 30 as described.

2. In a portable oxygen generator for medical purposes and the like, a casing, a flanged cover for said casing, spring clips adapted to hold the cover to the casing, a 35 gas collecting chamber depending from said cover, a vent in said cover outside of the said chamber, a receptacle detachably secured within said chamber by a bayonet joint, provided with the spring clip l , a horizontal partition in said receptacle, adjustable water passages through said partition, a vertical take-off pipe secured within the cylindrical casing at one side thereof, a horizontal tap connected with said pipe and extending 40 through the wall of the casing, an auxiliary chamber attached to the cover at one side of the gas collecting chamber and adapted to fit over the vertical take-off pipe, and a restricted passage between the said 45 auxiliary chamber and the gas collecting chamber, substantially as described.

3. In a portable oxygen generator for medical purposes and the like, a casing, a cover for said casing, a gas collecting chamber depending from said cover, a receptacle detachably secured within said chamber and extending below the lower end thereof, restricted openings in the walls of said receptacle below the gas collecting chamber, 55 a horizontal partition in said receptacle above said openings, water passages through said partition, an auxiliary chamber at one

side of the gas collecting chamber a restricted passage between said chambers, outlet connections from the auxiliary chamber and a cock in said connections, substantially as described. 65

4. In a portable oxygen generator for medical purposes and the like, a casing, a cover for said casing, a gas collecting chamber open at the lower end depending from 70 said cover, a receptacle secured to said chamber in the lower end thereof, a perforated partition in said receptacle, concave perforated plates swiveled above and below 75 said perforations, a stuffing of pervious material between the plates and the partition, outlet connections from the gas collecting chamber and a cock in said connections, substantially as described. 80

5. In a gas generating apparatus of the character described, a water chamber, a receptacle for the gas generating material having a perforated partition which separates it from the water chamber, concave perforated 85 plates swiveled above and below the perforations in said partition, a stuffing of pervious material between the plates and the partition, a gas collecting chamber with which the receptacle communicates, and outlet 90 connections from the gas collecting chamber, substantially as described.

6. In a portable oxygen generator for medical purposes and the like, a cylindrical casing a having the spring clips l , and a vertical take-off pipe supported within the casing at one side thereof and having a lateral tap b' extending through the wall of the casing and provided with a cock, in combination with a flanged cover for the casing 95 which is engaged by the spring clips l , a cylindrical tube depending from the cover and forming a gas-collecting chamber, a receptacle f detachably connected to the said tube and extending below the lower end 100 thereof, a perforated partition h within said receptacle, concave perforated disks i swiveled on said partition above and below the perforations therein, and a stuffing of pervious material between the plates and the 110 partition, and a sheet of metal p secured to one side of the depending tube to form an auxiliary chamber adapted to fit over the vertical take-off pipe when the cover is in place, the wall separating the gas collecting 115 chamber from the auxiliary chamber having a restricted passage, substantially as described.

In testimony whereof I affix my signature, in presence of two witnesses.

ANDRÉ BELTZER.
